UNITED STATES PATENT OFFICE.

GEORGE F. BROTT, OF WASHINGTON, DISTRICT OF COLUMBIA, ASSIGNOR
OF FOUR-FIFTHS TO ROBERT N. HARPER, CORNELIUS B. HITE, WILLIAM
B. MARSHALL, AND ROBERT BROTT, OF SAME PLACE.

COOKING STOVE OR RANGE.

SPECIFICATION forming part of Letters Patent No. 668,599, dated February 19, 1901.

Application filed November 21, 1900. Serial No. 37,209. (No model.)

To all whom it may concern:

Be it known that I, GEORGE F. BROTT, a citizen of the United States, residing at Washington, District of Columbia, have invented 5 certain new and useful Improvements in Cooking Stoves or Ranges, of which the following is a specification.

My invention is designed for the production of a cooking stove or range adapted to 10 employ either coal or wood or gaseous fuel and in which the heat generated may be utilized for cooking purposes and for the heating of a house by a hot-water system.

The primary object of my invention is to 15 provide a combined cooking and house-heating stove or range which will enable a separate furnace in the cellar for the heating of the house to be dispensed with.

A further object of the invention is to provide 20 means whereby coal or gaseous fuel may be independently employed for cooking and heating purposes and whereby gas may be used during warm weather for cooking purposes independently of the house-heating 25 system.

Other objects of the invention will hereinafter appear, and the novel features thereof will be set forth in the claims.

In the drawings forming part of this specification, Figure 1 is a vertical transverse section of a stove or range constructed according to my invention. Fig. 2 is a top plan view of the same, and Fig. 3 is a similar view of the water-tank or boiler.

Like reference-numerals indicate like parts in the different views.

The shell of the stove is made up of the sides 1, the bottom 2, and the top 3, all suitably secured to each other. The sides 1 are 40 provided with openings or ports 4 near their upper ends and are inclosed by a casing 5, secured at its upper end to the top 3 and having its lower end open. In the top 3 are formed a series of rows of pot-openings closed by the removable lids 6 6 7 7 8 8, preferably arranged parallel to each other.

Secured within the stove, at a point intermediate its top and bottom ends, is a water-tank or boiler 9, the same being provided

with water-legs 10, which extend down to and 50 rest upon the bottom 2. These water-legs 10 are formed with inwardly-extending lugs 11, which support a grate 12, of ordinary construction, extending clear across the stove.

Formed in the tank or boiler 9 at points directly beneath the lids or covers 6 and 8 in the top 3 are tubular passages 13 13, in which fit the flues 14, the same extending vertically therefrom and terminating at their upper ends a short distance below the lids 6 and 8. The 60 passages through the flues 14 are controlled by dampers 15, mounted above the upper ends of said flues and connected to operating-rods 16 16, extending out through the front wall of the stove. By moving these operating-rods in one direction or the other the dampers 15 may be moved to a position directly over the flues 14 or to a position out of line therewith. Of course when said dampers are directly over the flues 14 the passage therethrough is closed, and when they are out of line with said flues the passage through the latter is open. The flues 14 project at their upper ends through and are supported by a horizontal partition 17, located a 70 short distance beneath the top 3 of the stove, forming a space 18 through which the products of combustion pass on their way to the chimney 19. Also extending transversely of the stove and located in the space 18 directly 80 in front of the chimney 19 is a partition 20, which serves to deflect the products of combustion entering the space 18 from the flues 14 around the rear ends of the stove, so that they will enter the lower end of the chimney 85 19 from opposite sides.

Pivotal mounted in the partition 20 and in the front wall of the stove are rods 21 21, having secured to them dampers 22 22, extending longitudinally of the stove in the 90 space 18 and serving to cut off the sides of the space 18 from the central portion thereof. These dampers are located between the central row of openings in the top 3, which are covered by the lids 7, and the outer rows 95 of said openings.

Located centrally of the stove, between the flues 14 on opposite sides of the stove and

beneath the partition 17, is an oven 23, the same being supported in any suitable manner from the water-tank or boiler 9. In this oven is located a detachable gas-burner 24, connected with any suitable source of supply, and beneath the tank or boiler 9 is a similar gas-burner 25. In the space 18, directly beneath each of the lids 7 of the central row of pot-openings in the top 3, is a gas-burner 26, the burners 25 and 26 being also connected with a suitable source of gas-supply.

Leading from the upper part of the boiler 9 is an uptake-pipe 27, and leading into one of the legs 10 of the tank 9, near its lower end, is a downtake or return pipe 28. The pipes 27 and 28 are connected with the radiators of the house-heating system in the usual manner.

In the partition 17, above the burner 24, is an opening or openings leading into the oven 23, controlled by a slide or damper 29. Similar openings are formed in the sides of the oven 23, controlled by the slides or dampers 30.

The operation of my improved stove or range is as follows: When it is desired to employ coal or other hard fuel in the stove and the stove is to be employed for house-heating as well as cooking purposes, a fire is built in the combustion-chamber upon the grate 12 and the tank 9, as well as the remainder of the hot-water system, is filled with water. The products of combustion impinging against the under side of the tank 9, as well as against the legs 10 thereof, heat the water in said tank, and the same is caused to circulate throughout the piping and radiators in the house, thereby heating the same. At the same time the products of combustion pass up through the flues 14, and thence out through the chimney 19 after passing around the partition 20. The oven is thereby heated not only from the water-tank 9 beneath the same, but from the heat of the products of combustion passing through the flues 14. The top of the stove is also heated by direct impact of the products of combustion from the flues 14 against the under side of the lids or covers 6 and 8. The oven 23 may thus be used in the usual manner for roasting or baking anything that is desired and the top of the stove may also be used for cooking purposes.

If it be desired that the whole of the top 3 of the stove be heated, the dampers 22 are turned to the position shown in dotted lines in Fig. 1 of the drawings, when the products of combustion from the flues 14 may pass inwardly to the center of the stove and heat the lids 7 and the intervening spaces between the same.

The casing 5, surrounding the sides 1 of the stove, serves to prevent too great a heat adjacent to the stove and also serves to draw in the cold air from the bottom of the room up through the lower open end of said casing, the same passing through the ports or

openings 4 into the space 18, and thence off through the chimney 19.

Instead of using coal or wood on the grate 12 as the means for supplying heat the burner 25 may be utilized, the same acting upon the water-tank 9 and upon the top 3 of the stove in the same manner as the products of combustion from the burning fuel on the grate 12.

In warm weather when no heating of the house is desired the stove or range may be used for cooking purposes by dispensing with the fire on the grate 12 and at the burner 25 and utilizing the burners 24 and 26. The burner 24 serves to heat the oven 23 and may also be used as a broiler, whereas the burners 26, located directly beneath the lids 7 of the openings in the top 3 at the center of the stove, serve to heat said lids, so that any articles of food may be cooked thereon.

The water-legs 10 on the tank 9 may of course be dispensed with, and for said tank I may substitute any other kind of receptacle in which the water may be heated. Where the term "tank" is used, therefore, in the following claims I intend that the same shall include such a tank as is specifically shown as well as any other form of tank, coil of pipe, and the like.

Having thus described my invention, what I claim as new, and desire to secure by Letters Patent, is—

1. In a stove or range, the combination with the shell thereof, provided with the usual pot-openings in its top, of a combustion-chamber, a water-tank above said combustion-chamber, an intermediate chamber situated between said tank and the top of the stove, and flues leading from the combustion-chamber, passing through said tank and said intermediate chamber and discharging beneath said pot-openings.

2. In a stove or range, the combination with heating means, of a water-tank above the same, a horizontal partition between said tank and the top of the stove, uptake and return pipes of a hot-water system communicating with said tank, flues leading through said tank and said partition into the space between said partition and the top of the stove, and a chimney communicating with the latter space.

3. In a stove or range, the combination with heating means, of a water-tank above the same, a horizontal partition between said tank and the top of the stove, uptake and return pipes of a hot-water system communicating with said tank, flues leading through said tank and said partition into the space between said partition and the top of the stove, a chimney communicating with the latter space, and an oven located between said flues in the space between said partition and said tank.

4. In a stove or range, the combination with heating means, of a water-tank having depending legs, the body of said tank located

above said heating means and said legs at the 5 sides thereof, a horizontal partition between the body of said tank and the top of the stove, an uptake-pipe of a hot-water system leading from the upper part of said tank and a return-pipe leading into one of the legs thereof, flues leading through said tank, extending above the same and projecting through said partition into the space between said partition and the top of the stove, a chimney communicating with the latter space, and an oven located between said flues in the space between said partition and said tank.

5. In a stove or range, having a series of 15 rows of openings in the top thereof provided with removable lids or covers, the combination with heating means, of a horizontal partition beneath said top forming a space, a chimney leading off from said space, a water-tank above said heating means, uptake and return pipes of a hot-water heating system communicating with said tank, flues having their ends open leading through said tank and said partition and located directly beneath the outer rows of said removable 25 covers, and longitudinally-extending dampers in said space for separating the space beneath the central row of openings from the spaces beneath said outer rows.

30 6. In a stove or range, having a series of rows of openings in the top thereof provided with removable lids or covers, the combination with heating means, of a horizontal partition beneath said top forming a space, a chimney leading off from said space, a water-tank above said heating means, uptake and return pipes of a hot-water heating system 35 communicating with said tank, flues having their ends open leading through said tank and said partition and located directly beneath the outer rows of said removable covers, longitudinally-extending dampers in said space for separating the space beneath the central row of openings from the spaces beneath said outer rows.

neath the outer rows of said removable covers, longitudinally-extending dampers in said space for separating the space beneath the central row of openings from the spaces beneath said outer rows, and independent heating means for the covers of the central row of openings, located in the space between said dampers. 45

7. In a stove or range, having a series of rows of openings in the top thereof provided with removable lids or covers, the combination with heating means, of a horizontal partition beneath said top forming a space, a chimney leading off from said space, a vertical partition in said space in front of said chimney terminating at its ends a short distance from the sides of the stove, a water-tank above said heating means, uptake and return pipes of a hot-water heating system 50 communicating with said tank, flues having their ends open leading through said tank and said horizontal partition and located directly beneath the outer rows of said removable covers, longitudinally-extending dampers in said space for separating the space 55 beneath the central row of openings from the spaces beneath the outer rows, the said dampers being rotatably mounted in said vertical partition and in the front of the stove, and independent heating means for the covers of the central row of openings, located in the space between said dampers. 60

In testimony whereof I have hereunto set my hand in presence of two subscribing witnesses.
